UNITED STATES PATENT OFFICE.

JAMES ELIAS MORGAN, OF HICKMAN COUNTY, KENTUCKY.

WATER-ELEVATOR.

SPECIFICATION forming part of Letters Patent No. 278,582, dated May 29, 1883.

Application filed February 26, 1883. (No model.)

To all whom it may concern:

Be it known that I, JAMES ELIAS MORGAN, of the county of Hickman and State of Kentucky, have invented certain new and useful 5 Improvements in Water-Elevators; and I do hereby declare the following to be a full, clear, and exact description of the invention, such as will enable others skilled in the art to which it pertains to make and use it, reference being 10 had to the accompanying drawings, which form part of this specification.

My invention relates to an improvement in water-elevators; and it consists in the combination of a crane or derrick which is adapted 15 to swing around from its own weight, and which is provided with a pivoted latch for holding the crane over the well, and which latch has connected to its outer end a guide through 20 which the rope is passed, and against the lower end of which the bucket that is being raised from the well strikes for the purpose of raising the latch upward, as will be more fully described hereinafter.

The object of my invention is to provide a 25 water-elevator in which the crane or derrick is locked in position over the well while the bucket is being lowered into the well, but which is released as soon as the bucket is raised to that point where it is free to swing 30 around over the top of the well-curb, and thus save the trouble of having to lift it out of the curb and empty it.

Figure 1 is a side elevation of my invention. Fig. 2 is a plan view of the same. 35 A represents a suitable derrick or crane, which is pivoted eccentrically, so that it will swing around from over the top of the well from its own weight. Secured to this swinging frame or derrick is the windlass B, around 40 which the well-rope is passed. This rope extends upward and over the pulley C, which is journaled in the outer end of the crane, and from thence passes down and is attached to

the bucket. The windlass is provided with a crank and a ratchet, in the usual manner, so as 45 to hold the bucket at any desired point. When the derrick is left free it swings around from over the top of the well for the purpose of delivering the bucket at any point to be emptied; but when the bucket is to be lowered into the 50 well the crane is pushed around so as to stand directly over the top of the well.

Pivoted to one side of the horizontal portion of the crane or derrick is the latch G, which has connected to its outer end the rod J, which 55 has its lower end formed into a loop to serve as a guide for the well-rope. When the crane or derrick is swung around over the top of the well the latch catches over the top of the catch I and holds the crane rigidly in position over 60 the well, so that the bucket can be lowered to be filled with water, and then drawn up to a point above the top of the well-curb before the crane or derrick swings around. When the bail of the bucket strikes against the lower 65 end of the rod which is attached to the outer end of the latch, it raises the latch upward, so as to release it from the catch, and then the weight of the bucket causes the crane to swing around from over the top of the well to a point 70 where it can be emptied.

Having thus described my invention, I claim—

The combination of a crane or derrick, a latch which is pivoted thereto, and which has 75 a rod or stop attached to its outer end, a windlass, and the well-rope, the parts being combined and arranged to operate substantially as shown and described.

In testimony whereof I affix my signature in 80 presence of two witnesses.

JAMES ELIAS MORGAN.

Witnesses:

JOHN J. LATTA,
I. B. AUSTIN.
